METALWORKING APPARATUS AND
METHOD

Jan Kafawi, Far Rockaway, N. Y.

Application January 17, 1941, Serial No. 374,922

8 Claims. (Cl. 78—60)

The present invention relates to a method and apparatus for working metals and more particularly to a method and apparatus in which virgin metal, scrap metal and other metal stock is melted and cast into a larger ingot and then this larger ingot is pressed or extruded into smaller ingots each having the approximate size and weight for drop forging or pressing or warm pressing into the desired final or intermediary configuration and size.

It is of course known that warm or drop forgings are manufactured from drawn or otherwise produced metal rods by sawing the required length and weight ingots from the rod, the ingots being then placed in the dies and forged or pressed into the required configuration. It is quite expensive to produce metal parts or elements from stock rods since the rods must in most cases be sawed into the proper size which requires accurate work and produces considerable waste metal. This is avoided according to the present invention in that the method and apparatus utilize metallic ferrous or non-ferrous material in the form of pigs or bricks which is cast into a larger ingot and subsequently subdivided by hot pressing into smaller ingots each of the proper shape and weight for the subsequent warm forging or pressing step into the required and desired configuration.

It is, therefore, an object of the invention to subdivide by pressing, particularly in the heat, in a mold a larger ingot into a desired number of smaller ingots of required individual size and shape.

It is another object of the invention to subdivide a larger metallic ingot by pressing, particularly in the heat, in a mold into a desired number of smaller ingots of required individual size and shape and to impart to these smaller ingots a desired density.

It is still a further object of the invention to subdivide a larger metallic ingot by pressing, preferably in the heat, into a number of smaller ingots and to use as the larger ingot a casting which is substantially homogeneous and free of fissures, folds and holes so that the smaller individual ingots obtained by pressing them in the mold are of similar homogeneity as well as of the shape and size required.

It is, however, an object of this invention to cast the ingots of the required size and weight and which are free of any fissures, depressions or other faults which are known to occur in casting ingots as carried out heretofore. A further object of the invention resides in casting ingots

which are homogeneous and integral throughout without faults of such metals as copper, nickel, lead, zinc, aluminum, magnesium and their alloys, especially brass and bronze.

5 It is therefore an important feature of this invention to cast ingots, for the warm pressing or drop forging of various configurations which are free of bubbles, folds, cone shaped fissures, central channels, etc., in the form in which the diameter or lateral distance is approximately twice the thickness or vertical distance.

Thus an object of this invention also resides in providing an ingot and a mold for casting brass, bronze, and other metal alloys and metals 15 in which the lateral dimension of the mold and the ingot cast therein is approximately double the thickness or vertical dimension.

A still further object of the invention resides in a special apparatus for carrying out the shaping of the ingots both as to casting and pressing them out thereafter into smaller ingots of the required size and weight.

Further objects will be apparent from the following description when considered in connection with the accompanying drawings in which:

Fig. 1 is a diagram illustrating the process or processes according to the invention,

Fig. 2 is a cross section of a well known molded and cast ingot,

30 Fig. 3 is a vertical sectional view of a mold and ingot,

Fig. 4 is a vertical sectional view of a portion of a press for forming a plurality of ingots,

Fig. 5 is a plan view of a forming die for a 35 plurality of ingots,

Fig. 6 is a side view partly in section of the press on a smaller scale, and

Fig. 7 is a side elevation of a modified detail.

In accordance with the process metal pigs, 40 metal stock, or scrap metal 1, Fig. 1, such as of copper, nickel, zinc, aluminum, magnesium and their alloys, particularly brass and bronze, is melted in a furnace 2 and may be poured or cast in a mold 3 into the ingot 4 having the required amount of metal, that is the desired configuration and weight to be processed afterwards. In particular, the molten metal in 2 may be cast 45 into a large ingot 7 in a mold 8 and ingot 7 then pressed by extrusion into a plurality of small ingots 9 in the extrusion press 10. Each ingot 9 has the desired weight and size to be pressed preferably individually, into the finished or semi-finished articles 11 in a shaping press 12. As an alternative the molten metal may be cast in a mold 13 into a large billet 14 and the latter is

55

sheared or sawed into a number of ingots 15. Each ingot 15 is then placed in an extrusion press 16 and extruded into a plurality of small ingots 17 each of which is of the required size and weight to be drop forged or otherwise finished in the shaping press 18 to the finished or semi-finished articles 19. It is of course obvious that a metal working plant may comprise all the units and follow all the steps diagrammatically illustrated in Fig. 1.

As illustrated in Fig. 2 of the drawings it is of course well known that in casting ingots of various metals such as brass there results a depressed portion or fissure 20 which projects into the body of the casting for a considerable depth, depending upon the thickness or depth of the ingot 21. It has therefore been determined, and this constitutes an important feature of the invention, that in order to avoid any holes, faults or fissures in the casting the lateral dimension of the casting or ingot 23, Fig. 3, or the diameter as in the case of a circular casting, must be approximately twice the thickness or vertical dimension of the casting. This will prevent the formation of hollows or air bubbles and also prevents a suction manifestation taking place in the center of the casting. It is therefore advantageous that the mold 3, 8, for instance shown in Fig. 3 which may be made of any suitable material such as iron, must have a vertical dimension *a* of the mold cavity 22 which is approximately one-half of the width, diameter or lateral dimension *b*. It is not necessary that the relationship of the width to the depth is exactly two to one but it may vary slightly; however, the greater the variation, the more pronounced will be the slight central depression which may be formed in the casting. If the relationship of the width of the mold cavity to the depth is close to two to one, then only a very slight or practically no depression will form in the upper surface of the central part of the casting. However, such slight depression if formed will not be detrimental to the subsequent pressing or extrusion step of the cast ingot into the plurality of ingots or the finished article.

A further feature of the present invention resides in casting a rather large ingot such as the one indicated in Fig. 4 in which the ingot 30 is first cast as a rather large block of metal material which comprises a great deal more material than is required for the single articles to be shaped into the finished form. The ingot 30 is cast preferably under the same conditions and dimensions as has been described, that is the width of the ingot is approximately twice its thickness. This ingot 30 is placed in a die 32 in a die receptacle or die member 31 of an ingot molding machine or die press 33, Fig. 6. This die 32 may have any desired configuration such as for instance shown in Fig. 5 in which there are seven cavities 34 in which the ingots are formed by extrusion. The die 32 is contained in the casing 35 which is made of iron or steel or any other suitable material. Die 32 itself is preferably made of hardened high quality steel. The casing 35 also comprises a lower member 36 which is provided with the same number of openings 37 corresponding to the number of mold cavities 34. A plunger 38 is provided with a plate portion 39 on which a plurality of ejecting rods 40 are secured or rest. These ejecting rods 40 are each provided with an upper head portion 41 extending into the

mold cavities 34. Fig. 4 illustrates an ingot 30 which is ready and in position in the receptacle 31 to be pressed into the cavities 34 down to the upper surfaces of the head portions 41 of the rods 40. A pressing head member 26 which may be operated in any suitable manner, such as by mechanical or hydraulic power or even by the use of steam is rapidly forced into the receptacle 31 and thus presses or extrudes the ingot 30 into the cavities 34 to form the individual ingots. As shown in Fig. 6, the head member 26 is secured in a slide member 48 which is reciprocated in the machine frame 42 by means of a spirally threaded rod 43 meshing with corresponding grooves in the frame 42. A friction wheel 44, having preferably a hard leather peripheral surface, cooperates with one or the other friction disc 45 mounted to rotate on and with the shaft 46 driven by any suitable means from a source of power to the gear 47. The discs 45 are axially shiftable so that one or other disc will contact and rotate the wheel 44 in one or the other direction. After the extrusion step, that is after the ingot 30 has been forced and extruded into the die cavities 34, plunger 26 moves upwardly and at the same time plunger rod 38 together with plate 39 and rods 40 is moved upwardly to force the somewhat cooled and shrunk ingots out of the die cavities; each such ingot is of the desired configuration and weight of metal material and is thereafter pressed individually into the finished article.

Fig. 6 shows the ingots 49 after they have been forced out of the die 32; they may be integrally connected by a more or less thin flash forming a kind of connecting plate 50 and can be easily knocked apart and thus separated. The slide member 48 is connected by suitable rods 51 with a cross yoke 52 to which is secured a central push rod 53 contacting the rod or plunger 38. Thus, after the extrusion step, with raising of the head member 26 also plate 39 together with ejecting rods 40 are raised to eject the ingots 49 from the cavities 34.

The operation of the extrusion machine is believed to be obvious but it may be mentioned that upon an extrusion operation of the machine with an ingot of metal in and on the die 32, the head member 26 increases its downward speed as the wheel 44 approaches the peripheral of the driving disc 45.

Referring to Fig. 7, it is a further feature of the invention that the ejecting rods 40 may be interchanged for rods 54 which may have any desired length in order to regulate the desired length of ingots which are to be extruded. Also an auxiliary plate or disc 55 may be employed having a certain thickness which may be interchanged with other plates of certain specific thickness. Both the plate 55 and the rods 54 may be interchanged simultaneously to secure the exact length of ingots, or the plates 55 alone or the rods 54 may be interchanged for this purpose.

It should also be understood that ingot 30, Fig. 4, which is of a size equalling the total of the sizes of the smaller individual ingots plus the volume of the flash, is preferably but not necessarily cast to a size the height or thickness of which amounts to approximately half its horizontal width or diameter, if a cylindrical blank is concerned the axis of which is about vertical when placed in die 32, whereby particularly dense smaller ingots are obtained by extrusion. However, this feature of the invention of subdividing

a larger ingot into a predetermined number of smaller ones can be successfully applied to a larger ingot of any other desired shape and proportions.

It should also be understood that the smaller ingots when separated by knocking off the connecting flash may be subjected to one or more subsequent shaping operations preferably in a cold or hot press or by drop forging, and the shaped body so obtained either be of the final shape ready for use or of an intermediary shape which facilitates further shaping or machining. In the first case a finished article, and in the latter case a semi-finished article is obtained.

It is of course obvious that this invention is not limited to the exact features described and illustrated but the various details are susceptible of variations within the scope of the appended claims. As to the extrusion step in connection with the various methods disclosed, it is understood that this step is used when a larger ingot is to be subdivided by pressing at proper heat into a number of smaller ingots of required shape and size. If the larger cast ingot is dimensioned in the way described above more in detail and therefore homogeneous and compact, the smaller ingots obtained therefrom will substantially retain this structure and even in most of the cases be more densified. By heating the larger initial ingot to proper temperature at which it can be easily and almost instantaneously pressed into the required shape, the cast and initially larger ingot is annealed and stresses in its crystalline structure are removed; during pressing the temperature of the material is somewhat lowered and the pressing action secures and maintains the compact crystalline structure of the material. The mold or die is heated by the subsequent moldings in regular operation to a degree of temperature which eventually remains almost constant whereby a desired rate of cooling of the smaller ingots is secured, and rapid cooling resulting in quenching can definitely be avoided. Thereby a desired crystalline structure of the smaller ingots is retained or obtained. Also during cooling, the smaller ingots shrink slightly but sufficiently to permit their easy and fast removal from the mold cavities by the ejecting rods.

I claim as my invention:

1. A device for subdividing by pressing, particularly extruding, a larger metallic ingot into a plurality of smaller ones, substantially comprising a die provided with a first larger cavity, and a plurality of second cavities of smaller individual cross sections than that of and in open communication with the former, said first cavity opening into a front of the die and said second cavities opening into an opposite front of the die, the total of the individual sizes of said second cavities exceeding the size of an ingot to be inserted into said first cavity, and ejecting members arranged to individually enter each of said second cavities from said opposite front of the die, so that by forcing a pressing member into said first cavity an ingot placed therein and covering openings of said second cavities can be pressed into the latter and thereby subdivided and the smaller ingots thus obtained can be ejected by forcing said ejector members into said second cavities.

2. A device for subdividing by pressing, particularly extruding, a larger metallic ingot into a plurality of smaller ones of required size, substantially comprising a die provided with a first larger cavity and a plurality of second cavities

in open communication with the former, the cross sections of said second cavities substantially corresponding to those required of the smaller ingots and their axial lengths being such that the total of the individual sizes of said second cavities exceeds the size of an ingot to be placed into said first cavity, said first cavity opening into a front of the die, and said second cavities opening into the opposite front of the die, and ejecting members arranged to individually enter each of said second cavities from said opposite front of the die, so that by forcing a pressing member into said first cavity an ingot placed therein and covering openings of said second cavities can be pressed into the latter and thereby subdivided into smaller ingots of required size, and the latter be ejected by forcing said ejector members into said second cavities.

3. A device for subdividing by pressing, particularly extruding, a larger metallic ingot into a plurality of smaller ones of required size, substantially comprising a die provided with a first larger cavity and a plurality of second cavities in open communication with the former, said first cavity opening into a front of the die and said second cavities opening into an opposite front of the die, the individual cross sections of said second cavities substantially corresponding to those of the smaller ingots and the axial lengths of said second cavities being such that the total of the individual sizes of said cavities exceeds the size of an ingot to be placed in said first cavity, ejecting members individually associated with each of said second cavities and arranged to enter them from said opposite front of the die, the entering ends of said members shaped so as to close the associated cavity, and means for adjusting said members in a predetermined rest position within said second cavities and forcing said members further into said cavities, so that by forcing a pressing member into said first cavity an ingot of predetermined size placed therein can be pressed into said second cavities and thereby subdivided into smaller ingots of a size predetermined by the sizes of said smaller cavities and the rest position of said members, and the smaller ingots thus formed be ejected by forcing said members further into the associated cavities.

4. In combination with a power press, such as an extrusion press for subdividing a larger ingot into a plurality of smaller ones, a die having opposite fronts, a first and larger cavity in said die opening in one of said fronts for receiving an ingot and pressing head, a plurality of second cavities of considerably smaller individual cross sections than that of said first cavity, said second cavities opening at one end into said first cavity and at their other end into the second of said fronts, rod-like members slidably arranged in each of said cavities and projecting outside said second front, and movable means as exemplified by a plunger arranged outside said second front for adjusting a rest position of said members during pressing and for forcing said members into said cavities for ejecting a pressed work.

5. In combination with a power press, such as an extrusion press for subdividing a larger ingot into a plurality of smaller ones, a die having opposite fronts, a first and larger cavity in said die opening into one of said fronts for receiving an ingot and pressing head, a plurality of second cavities in said die of considerably smaller individual cross sections than that of said first cavity, said second cavities opening at one end into said first cavity and at the other end in the sec-

ond of said fronts, a block arranged at said second front and provided with bores aligned with said second cavities, rod-like members slidably arranged within and projecting outside said bores, and movable means as exemplified by a plunger arranged to cooperate with the projecting ends of said members for adjusting the latter in predetermined rest position during pressing and for forcing said members into said cavities for ejecting a pressed work.

6. In combination with a power press, such as an extrusion press for subdividing a larger ingot into a plurality of smaller ones, a die having opposite fronts, a first and larger cavity in said die opening in one of said fronts for receiving a pressing head and an ingot the height of which approximates half of its largest lateral dimension, a plurality of second cavities in said die of considerably smaller individual cross sections than that of said first cavity, said second cavities opening at one end into said first cavity and at the other end in the second of said fronts, said second cavities arranged substantially parallel to the direction of pressing, rod-like slidable members individually associated with each of said second cavities and having ends shaped to form a bottom of the associated cavity, said members projecting outside said second front, and movable exchangeable means as exemplified by a plate arranged to cooperate with the projecting ends of said members for holding the latter in predetermined position during pressing and forcing them further into said second cavities for ejecting a pressed work.

7. A device for subdividing by pressing, particularly extruding, a large metallic ingot into a plurality of smaller ones, substantially comprising a die provided with a first larger cavity and a plurality of second cavities of smaller individual cross sections than that of and in open communication with the former, said first cavity

opening into a front of the die and said second cavities opening into an opposite front of the die, the size of said first cavity being such so as to receive the working end of a pressing member and an ingot the height of which approximates half of its largest lateral dimension, the total of the individual sizes of said second cavities exceeding the size of an ingot to be inserted into said first cavity, and ejecting members arranged to individually enter each of said second cavities from said opposite front of the die, so that by forcing a pressing member into said first cavity an ingot placed therein and covering openings of said second cavities can be pressed into the latter and thereby subdivided and the smaller ingots thus obtained can be ejected by forcing said ejector members into said second cavities.

8. A device for subdividing by pressing, particularly extruding, a larger metallic ingot into a plurality of smaller ones, substantially comprising a die provided with a first larger cavity and a plurality of second cavities of smaller individual cross sections than that of and in open communication with the former, said first cavity opening into a front of the die and said second cavities opening into an opposite front of the die, said second cavities arranged substantially parallel to the direction of pressing and the total of their individual sizes exceeding the size of an ingot to be inserted into said first cavity, and ejecting members arranged to individually enter each of said second cavities from said opposite front of the die, so that by forcing a pressing member into said first cavity an ingot placed therein and covering openings of said second cavities can be pressed into the latter and thereby subdivided and the smaller ingots thus obtained can be ejected by forcing said ejector members into said second cavities.

JAN KAFOWI.
